UNITED STATES PATENT OFFICE.

ARTHUR A. KRAEUTER, OF SOUTH ORANGE, NEW JERSEY, ASSIGNOR TO THE KROYDON COMPANY, OF NEWARK, NEW JERSEY, A CORPORATION OF NEW JERSEY.

HANDLE GRIP AND METHOD OF MAKING THE SAME.

Application filed April 8, 1925. Serial No. 21,717.

This invention relates to improvements in handle grips and method of making the same and particularly to grips that are used on clubs, racquets, bats, etc. for sporting or athletic purposes and while its principal purpose and use may be in connection with golf clubs and golf shafts, it may be also used in connection with tennis racquets, baseball bats, polo mallets and other implements or articles for similar uses.

The principal purpose of this invention is the provision of a handle grip which may be readily and cheaply applied to the handle of the article and which will securely and evenly fit the same and which will be permanently secured thereto against loosening by accident or otherwise, and which in addition has the very important advantage of being waterproof and also becoming sticky or tacky or slightly adhesive when in use so as to afford a firm and secure grip by the user thereof.

This is very superior to the ordinary form of leather grips now in use which readily become unravelled and loosened due to stretching and breaking or wearing of the securing twine and which also become very slippery and at times unusable when wet.

To the accomplishment of the foregoing and such other objects as may hereinafter appear, this invention consists in the construction, combination and arrangement of parts hereinafter described and method of making the same, reference being had to the accompanying drawings forming a part hereof, and which show merely for the purpose of illustrative disclosure certain embodiments of the invention, it being expressly understood, however, that various changes may be made in practice within the scope of the claims without digressing from my inventive ideas.

In the drawings—

Figure 1 represents a view in perspective of the handle portion of a golf club with a grip constructed according to my invention;

Figure 2 is a vertical longitudinal section thereof.

It will be seen that this invention has been illustrated in the drawings as applied to a golf club or golf shaft and it is to be understood that this is for illustrative purposes only and that the invention is applicable to

the various articles hereinbefore enumerated as well as many others.

Referring now to the drawings the numeral 1 designates the shaft of the golf club to which the grip is to be applied. In this example a layer of felt 2 or other suitable material is tightly wrapped around the handle end of the shaft to assist in building it up to its proper softness and thickness. This layer of felt 2 is pasted, glued or otherwise secured to the shaft. On this layer of felt 2 is woven or plaited the grip 3 proper of suitable textile material. This is woven directly upon the handle by running the shaft through a suitable machine. It is woven very tightly so as to bind the felt very tightly to the shaft and so as to fit the shaft very tightly and securely and so as to present a firm and even outer surface. This results in the felt layer and the textile layer being securely attached to the shaft so that they will not slip or become disarranged.

On top of this layer of textile material 3 is applied a coating or a plurality of coatings of a lacquer 4 or other suitable material of a sufficient thickness to completely cover the textile material 3. It is possible that some of this coating penetrates through the felt and assists in holding the various layers of the grip together. Furthermore, this coating also has the function of preventing the textile layer from unravelling and from loosening from its applied position. At the same time the coating layer is of sufficient thinness so as to retain the impressions or indentations of the textile fabric or material of the outer surface so that this outer surface is slightly rough or uneven. While I have stated that the textile material is woven tightly so that it presents an even outer surface, it is to be understood that this is a relative term only and that although it is even, generally speaking, the separate threads cause alternate depressions and ridges and it is these alternate depressions and ridges that form the depressions and ridges in the outer coating 4. This outer coating 4 must have the following characteristics: It must be waterproof and it must become sticky or tacky or slightly adhesive in use due to the warmth of the user's hands; it also must have sufficient body to give extended use and service.

The method of making this handle grip,

- therefore, includes the following steps: first, wrapping a layer of felt or other suitable material about the gripping end of the shaft; second, weaving or plaiting securely thereon a textile fabric or material; and thirdly, coating this textile material with a lacquer or other suitable material which has the necessary characteristics as called for above.
- 10 It is to be understood that while I have described and shown a grip having the felt under layer, this layer may be omitted where desired and the grip consist of the woven or plaited textile material tightly secured to the gripping part of the handle and the layer of lacquer or other suitable material thereover.

This process is also advantageous in repairing articles of the kinds mentioned and 20 similar articles.

It is also to be understood that this layer or sleeve of woven textile material may be made and applied to the handle after it is made or woven. Then the layer of lacquer 25 or other suitable material 4 is applied which causes the textile layer to shrink fast on the shaft.

What I claim is:—

1. In combination with a handle or shaft, 30 a handle grip including a tube or sleeve of woven or plaited textile material on the gripping portion of the handle, and an outer coating of material thereon, said coating being of sufficient thickness so as 35 to be entirely impermeable to moisture and at the same time to reproduce the indentations or impressions of the textile material on the outer surface of said coating, said coating also being sticky, tacky or slightly adhesive when grasped by the hand in use.

2. A grip for a handle or shaft including a layer of woven or plaited textile material coated with a waterproof material which becomes sticky, tacky or slightly adhesive 45 when grasped by the hand in use, said coating being sufficiently thin to reproduce the surface roughness of the fabric on the surface of the coating, which is therefore slightly rough and uneven and affords a 50 firm gripping surface.

3. A grip for a handle or shaft including a layer of woven or plaited textile material and a coating of waterproof material securely anchored to said layer of textile material, said coating being sufficiently thin to 55 reproduce on its outer surface the surface

roughness of the fabric to afford a firm and secure grip for the hand.

4. The method of making a handle grip for golf shafts and the like including tightly 60 weaving or plaiting a layer of textile material on the gripping portion of the shaft and then coating said layer of textile material with a composition which has the characteristics of being waterproof and also 65 being sticky, tacky or slightly adhesive when in use.

5. The method of making a handle grip for golf shafts and the like including tightly 70 weaving or plaiting a layer of textile material on the gripping portion of the shaft and then coating said layer of textile material with a substantially thick layer of composition which has the characteristics of being waterproof and also being sticky, 75 tacky or slightly adhesive when in use.

6. The method of making a handle grip for golf shafts and the like including applying a tube or sleeve of woven or plaited 80 textile material on the gripping portion of the shaft and then coating said tube or sleeve of textile material with a composition which has the characteristics of being waterproof and also sticky, tacky or slightly adhesive 85 when in use, said composition causing the tube or sleeve to shrink fast on the shaft.

7. The method of making a grip for handles, shafts and the like including weaving or plaiting a layer of textile fabric 90 directly on the gripping portion of said handle, shaft or the like and then coating said layer of textile material with a layer of waterproof composition thin enough to reproduce the surface roughness of the textile layer on the outer surface of the coating.

8. The method of making an integral grip for handles, shafts and the like, including weaving or plaiting an integral 100 layer of textile fabric in the form of a tube directly and tightly on the gripping portion of the handle, shaft or the like, then coating said layer of textile fabric with a layer of waterproof composition thin enough to permeate the textile material and become securely anchored thereto to form an integral 105 part thereof.

In testimony that I claim the foregoing, I have hereunto set my hand this 4th day of April, 1925.

ARTHUR A. KRAEUTER.
